UNITED STATES PATENT OFFICE.

WILLIAM R. DAGGETT, OF DAYTON, OHIO.

ELECTRIC-RAILWAY SWITCH.

SPECIFICATION forming part of Letters Patent No. 561,970, dated June 16, 1896.

Application filed November 30, 1895. Serial No. 570,612. (No model.)

To all whom it may concern:

Be it known that I, WILLIAM R. DAGGETT, of Dayton, county of Montgomery, State of Ohio, have invented a new and useful Improvement in Electric-Railway Switches; and I do declare the following to be a full, clear, and exact description of the invention, such as will enable others skilled in the art to which it appertains to make and use the same, reference being had to the accompanying drawings, and to the figures and letters of reference marked thereon, which form a part of this specification.

My invention relates to improvements in electric switches for street-railways, and has for its object to provide an effective and simple switch-shifting mechanism, as will be hereinafter more fully described.

Referring to the annexed drawings, Figure 1 designates a view in perspective of a track having my improved switch devices thereon. Fig. 2 is a top view showing in section the case in which the electromagnets are placed. Fig. 3 is an end elevation of the track, showing the switch and inclosing case in section. Fig. 4 is a view in perspective of the trolley-wires and the cross-wires that are connected with the electromagnets.

In a detailed description of the invention, 30 1 and 2 designate, respectively, main and diverging tracks.

3 designates the tubular poles to which the cross-wires 4, that support the trolley-wires 5 and 6, are attached.

35 7 designates an inclosing case, which is provided with a suitably-insulated seat in the ground to a depth that enables the upper side 8 thereof to lie flush with the surface of the ground, as shown in Fig. 3, and provides a 40 flat surface for the switch-tongues 9 and 10 to slide upon.

11 and 12 designate two electromagnets that are inclosed within the case 7. To one end of the helix of each of the electromagnets are connected wires 13 and 14, and the other end of said helices have a ground connection $g g'$. The wires 13 and 14 are inclosed in and suitably insulated from the tubular posts 3. The upper ends of these wires 50 extend upwardly through said posts and horizontally above the trolley-wires 5 and 6 and are connected to a non-conducting piece 15.

16 designates an armature that lies between the magnets and rests upon flanged rollers 17 17, that are suitably mounted in the case 7. 55

18 and 19 are lugs or stops on the said armature and on the bottom of the case, which are adapted to limit the movement of the armature as it is attracted in either direction by the magnets. 60

20 and 21 are pins that project from the upper side of the armature and penetrate slots 22 in the upper side of the case 7 and have their upper ends secured to the switch-tongues 9 and 10. It will therefore be seen 65 that as the armature is alternately attracted by the electromagnets the switch-tongues will be shifted accordingly. The electromagnets are excited by the trolley-wheels making contact with the conductor-wires 13 and 14 and 70 conveying current from the trolley-wires.

For example, referring to Fig. 1, assuming that a car is approaching the switch in the direction of the arrow and is using the diverging track, the trolley-wheel in contact 75 with wire 5, when it reaches the wire 13, will convey current thereto, thus making a circuit for an instant between the trolley-wire and the electromagnet 11, which attracts the armature and therewith the switch in line 80 with the diverging track. The trolley-wheel in contact with wire 6 will perform a similar function to shift the switch back to the main line.

The switch-tongues 9 and 10 are pivoted 85 at $a a$, the ends farthest from the approaching car. Therefore I am enabled to dispense with the use of a frog.

Having described my invention, I claim—

In an electric switch for street-railways, the 90 combination with a switch, of electromagnets on the outside of said switch, an armature between said electromagnets, and connected to said switch, flanged rollers upon which said armature rests and is guided, wires 13 95 and 14 in the path of the trolley-wheels and adapted to convey current from the trolley-wires to said electromagnets.

In testimony whereof I have hereunto set my hand this 21st day of November, 1895.

WM. R. DAGGETT.
